US0D1011896S

(12) **United States Design Patent** (10) **Patent No.:** **US D1,011,896 S**
(45) **Date of Patent:** **** Jan. 23, 2024**

(54) **PET FOOD CONTAINER**

(71) Applicant: **Edmonds Outdoors, LLC**, Nashville, TN (US)

(72) Inventor: **Addison Edmonds**, Brentwood, TN (US)

(73) Assignee: **Edmonds Outdoors, LLC**, Nashville, TN (US)

(**) Term: **15 Years**

(21) Appl. No.: **29/752,270**

(22) Filed: **Sep. 25, 2020**

(51) **LOC (14) Cl. 09-01**

(52) **U.S. Cl.**

USPC **D7/629; D3/294**

(58) **Field of Classification Search**

(57) **CLAIM**

What is claimed is the ornamental design for an “pet food container”, as shown and described.

DESCRIPTION

FIG. 1 is a front perspective view of the “pet food container” of Applicant’s invention.

FIG. 2 is a rear perspective view of the “pet food container” of Applicant’s invention.

FIG. 3 is a right side view of the “pet food container” of Applicant’s invention.

FIG. 4 is a left side view of the “pet food container” of Applicant’s invention.

FIG. 5 is a front view of the “pet food container” of Applicant’s invention.

FIG. 6 is a back view of the “pet food container” of Applicant’s invention.

FIG. 7 is a top view of the “pet food container” of Applicant’s invention; and,

FIG. 8 is a bottom view of the “pet food container” of Applicant’s invention.

The dashed lines in the drawings represent environmental structure that forms no part of the claimed invention.

1 Claim, 8 Drawing Sheets
